UNITED STATES PATENT OFFICE

103,690

DESIGN FOR A CHAIR

Ferdinand Racen, St. Louis, Mo., assignor to W. G. Shelton Company, St. Louis, Mo., a corporation of Missouri

Application February 1, 1937, Serial No. 67,383

Term of patent 7 years

To all whom it may concern:

Be it known that I, Ferdinand Racen, a citizen of the United States, residing at St. Louis, Missouri, have invented a new, original, and ornamental Design for a Chair, of which the following is a specification, reference being had to the accompanying drawing, forming part thereof.

I claim:

The ornamental design for a chair substantially as shown.

FERDINAND RACEN.
